UNITED STATES PATENT OFFICE.

PETER VILHELM CHRISTIANSEN, OF COPENHAGEN, DENMARK.

ADJUSTABLE PAD.

Application filed December 26, 1922. Serial No. 609,121.

To all whom it may concern:

Be it known that I, PETER VILHELM CHRISTIANSEN, a subject of the King of Denmark, and resident of Copenhagen, in the Kingdom of Denmark, have invented new and useful Improvements in Adjustable Pads, of which the following is a specification.

My invention relates to a pad, which, at the same time as it is adjustable in the height, remains closed in its sides in all positions.

My invention is illustrated in the accompanying drawing, in which—

15 Figure 1 shows the adjusting mechanism of the pad, and

Fig. 2 a vertical cut through the middle of the pad, on a larger scale.

The pad is mounted on two frames 2 and 20 3 being along the foresides hinged together through hinges 1. The frame 2 forms the support of the pad, while the cover 4 is placed on the upper frame 3. In the frames are lodged two slides 5 and 6, consisting for 25 instance of angle- or U-irons, and being movable on pivots 7. At each end of the slide 5 is turnably lodged a bar 8, which with its free end can glide on the slide 6, and at each end of the slide 6 a similar bar 9 is turnably lodged, which with its free end 30 slides on the slide 5. The bars 8 and 9 are in the middle coupled together in pairs by means of bolts 10, so that they form two scissars. At each end of the slide 6 is, 35 besides, on bolts 11 a rack 12 turnably lodged. The racks 12, being together a little longer than the slide itself, and having oppositely directed teeth, are held down by springs 13, placed about the bolts 11 and 40 being lodged in the slide 6. Near the free ends of the bars 8 a movable bow 14 is placed, which is furnished with a cross-piece 15, and each grasps about one of the racks 12, so that the teeth of the same by the 45 action of the spring 13 engage with the cross-piece 15, which may be shaped as a bolt. The racks are movably coupled together and, on the connecting-bolt 16, furnished with a drag-rope 17, reaching out of the 50 pad, for instance by going through the upper frame.

At the back-side of the cover 4 or on the top of the upper frame a strap 18 is placed. Between the two back-sides and the four 55 shorter sides of the frames 2 and 3 covers

19 and 20 are placed, which close the pad, thus hiding the adjusting mechanism.

When the pad has to be raised from its collapsed position, in which the frames 2 and 3 are resting on each other, and the covers 19 and 20 thus are folded together, the strap 18 is lifted up, so that the slide 6 is raised, and the scissars 8, 9 are shut more or less. When the strap is dropped again, the pad will be adjusted in a certain height, in which it will be held by the engagement between the racks 12 and the cross-pieces 15. If the pad has been lifted to its highest position, the covers 19 and 20 will be stretched out.

When thereupon the pad has again to be lowered more or less, the engagement between the racks and the cross-pieces must be temporarily broken off. This is effected by pulling the drag-rope 17, so that the racks 75 12 against the action of the springs 13 are lifted and thus get free of the cross-pieces 15. The scissars are then opened, the free ends of the bars 8 and 9 approaching each other, when the upper frame is swung down. 80 As soon as the action of the drag-rope on the racks 12 ceases, the engagement between the racks and the cross-pieces 15 takes place again, so that the pad is fastened in a lowered position.

The pad, which may be used as a common pad, and the lower frame of which can be provided with straps for fastening in the mattress or the bed, is especially useful for sick-beds and beds of hospitals, but it can 90 also be solidly covered-in in divans or mattresses. The upper and the lower frame can either be of the same breadth or, as shown in the drawing, of different breadths, and the adjusting mechanism may be used by 95 movable flats, which have to be raised to and held in different slanting positions. Thus the adjusting mechanism can for instance be used by drawing-boards and the like.

Having thus described my invention, I claim:

In adjustable pads the combination of an upper frame, a transverse channeled slide turnably mounted in the same frame; a lower frame, a channeled slide parallel to the first named slide and turnably mounted in the lower frame; pairs of pivotally connected cross-bars, one pair at each end of the pad, in each pair one bar being pivotally 105 110

mounted in the channel of the upper slide and having the lower end slidable in the channel of the lower slide, the second bar of each pair being pivotally mounted in the channel of the lower slide, and having its upper end slidable in the channel of the upper slide; two racks, each pivotally connected respectively at its outer end to an outer end of the upper slide and having oppositely directed teeth; springs for holding the said racks down; means for connecting the adjacent inner ends of the said racks; a drag rope for lifting the said racks against the action of the springs; bows placed near the slidable end of the bars

which are pivoted to the lower slide, each of said bows encircling an adjacent rack; cross-pieces connecting said bows to said bars respectively, said cross-pieces engageable with the teeth of said racks, so that the upper frame is held lifted as long as the said drag rope is left uninfluenced, while it can be lowered by pulling the drag rope to lift the racks out of engagement with the teeth of the cross-pieces to allow the pairs of cross-bars to spread. 20 25

In witness whereof I have hereunto set my hand.

PETER VILHELM CHRISTIANSEN.
